UNITED STATES PATENT OFFICE.

WILLIAM J. KELLY, OF CLINTON, IOWA.

DESIGN FOR A FASTENING-PLATE FOR UPHOLSTERY-BUTTONS.

SPECIFICATION forming part of Design No. 29,738, dated November 29, 1898.

Application filed October 31, 1898. Serial No. 695,134. Term of patent 14 years.

To all whom it may concern:

Be it known that I, WILLIAM J. KELLY, a citizen of the United States, residing at Clinton, in the county of Clinton and State of Iowa, 5 have invented and produced a new and original Design for a Fastening-Plate for Upholstery - Buttons, of which the following is a specification.

My invention relates to a new securing or 10 fastening plate for upholstery-buttons, and is illustrated in the accompanying drawings, in which—

Figure 1 is a front view of the plate; Fig. 2, a rear view, and Fig. 3 a cross-section.

15 The leading feature of my design consists in a fastening-plate for upholstery-buttons bent or depressed transversely across one of its diameters to present two slightly-separated walls extending substantially at right angles 20 to the face of the plate and having a perforation in the bottom of the bend or depression.

In the said drawings the reference-numeral

1 indicates the securing or fastening plate, which is bent or depressed across one of its diameters to present two slightly-separated 25 walls 2 3, extending substantially at right angles to the face of the plate and having a perforation 4 in the bottom of the bend or depression.

My design presents a new and distinguishing appearance.

Having thus described my invention, what I claim as new, and desire to secure by Letters Patent, is—

The design for a fastening-plate for upholstery-buttons substantially as herein shown and described.

In testimony whereof I have hereunto set my hand in presence of two subscribing witnesses.

WILLIAM J. KELLY.
